US0D1043602S

(12) **United States Design Patent** (10) **Patent No.:** **US D1,043,602 S**
(45) **Date of Patent:** **** Sep. 24, 2024**

(54) **ELECTRONIC DEVICE**

(71) Applicant: **Samsung Electronics Co., Ltd.**, Suwon-si (KR)

(72) Inventors: **Dahyun Lee**, Suwon-si (KR); **Jinhoo Lee**, Suwon-si (KR); **Namsu Kim**, Suwon-si (KR); **Junwon Lee**, Suwon-si (KR); **Miri Lee**, Suwon-si (KR); **Jieun Myung**, Suwon-si (KR); **Jiyoung Lim**, Suwon-si (KR)

(73) Assignee: **SAMSUNG ELECTRONICS CO., LTD.**, Suwon-si (KR)

(**) Term: **15 Years**

(21) Appl. No.: **29/863,212**

(22) Filed: **Dec. 16, 2022**

(30) **Foreign Application Priority Data**

Jun. 17, 2022 (KR) 30-2022-0024289

(57) **CLAIM**

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The dashed broken lines in the figures depict portions of the electronic device that form no part of the claimed design.
